[57] ABSTRACT

Tris(2-carboxyethyl)isocyanurate and esters, amides, anhydrides and acid halides thereof undergo pyrolysis to afford cyanuric acid and acrylic acid or the corresponding ester, amide, anhydride or acid halide thereof. The process provides an in situ source of acrylate derivatives.

11 Claims, No Drawings

PYROLYSIS OF TRIS(2-CARBOXYETHYL)-
ISOCYANURATE

BACKGROUND OF THE INVENTION

This invention relates to a method of preparing acrylic acid and derivatives thereof, and in particular, relates to a method of preparation of acrylates from tris(2-carboxyethyl) isocyanurate and derivatives thereof.

Derivatives of isocyanuric acid are known to react in a variety of ways under pyrolysis conditions, depending upon the substituents pendant from the triazine ring. For example, U.S. Pat. No. 3,108,115 discloses that the tris(2-hydroxyethyl) derivative undergoes detrimeration upon being subjected to elevated temperatures, especially at reduced pressure, to afford 2-oxazolidones. Alkyl esters of isocyanuric acid, on the other hand, hydrolyze to carbon dioxide and primary amines upon being heated in the presence of base. Karrer, *Organic Chemistry* (4th Eng. ed., 1950) p 237. However, Smolin et al., *s-Triazines* (1959) p 406-407, indicates that variation of the base can give other products such as triethylbiuret, ethylene, ethanol, and triethylguanidine, and at page 402 indicates that pyrolysis under acidic conditions affords isocyanates. Carboxyl-substituted isocyanurates, on the other hand, are reported as being relatively stable under conditions which would pyrolyze other isocyanurate derivatives. For example, West German Pat. No. 812,312 of Aug. 27, 1951, discloses that the triethyl esters of tris(3-carboxypropyl)isocyanurate and tris(carboxymethyl)isocyanurate can be subjected to temperatures as high as 250° C. at reduced pressure without decomposition. Similarly, U.S. Pat. No. 3,230,220 discloses that tris(carboxymethyl)isocyanurate is substantially more stable on heating than is the ethyl homolog.

SUMMARY OF THE INVENTION

It has now been found that tris(2-carboxyethyl)isocyanurate and derivatives thereof undergo pyrolysis to afford acrylic acid and derivatives thereof. In addition to the free carboxylic acid, derivatives of tris(2-carboxyethyl)isocyanurate which undergo analogous pyrolysis include esters, amides, acid halides and anhydrides thereof, thereby affording a synthesis of various acrylate derivatives difficult to obtain otherwise.

The reaction is useful as a means of providing a high temperature in situ source of a variety of acrylic acid derivatives which are obtained in surprisingly pure form. Cyanuric acid, or tautomeric isocyanuric acid, is a valuable by-product of the pyrolysis reaction, and can be recycled in the process. The formation of cyanuric acid is especially unexpected in that C-N scission in isocyanurate derivatives has never before been observed to leave the triazine ring intact.

DETAILED DESCRIPTION OF THE INVENTION

The instant invention involves a pyrolysis reaction unique among isocyanurate derivatives whereby acrylic acid derivatives are obtained and the triazine ring is left intact. The process proceeds according to the following sequence:

and includes within its scope the various derivatives of carboxylic acids, e.g., esters, amides, acid halides, acid anhydrides and other carboxylic acid derivatives. The reaction also includes within its scope the pyrolysis of homologs of tris(2-carboxyethyl)isocyanurates, viz., tris(2-carboxypropyl) and tris(2-carboxybutyl)isocyanurates and the ester, amide, acid halide and anhydride derivatives thereof. Thus, the reaction provides a method of obtaining acrylic acid, alkyl acrylates, acrylamide, acryloyl chloride, various acrylic acid anhydrides, methacrylates, ethacrylates and other related acrylic acid derivatives from the correspondingly substituted carboxyethyl isocyanurate. Hereinafter these derivatives are collectively referred to as "carboxylic acid derivatives" of the isocyanurate or acrylic acids. The reaction is conducted under conditions sufficient to result in the desired pyrolysis of the isocyanurate reactant. The reaction requires elevated temperatures, although the required minimum temperature to afford pyrolysis will vary with the particular isocyanurate selected as reactant, desired rate of reaction, reaction pressure, and other considerations disclosed hereinafter. Typically, the reaction temperature for the instant process will be at least about 150° C., preferably within the range of about 170° - 250° C. Of course, temperatures outside this range may be found to be adequate in any particular reaction and the use of such temperatures is within the scope of the instant invention. The most advantageous temperature to be employed in any particular instance can be readily determined by simple experimentation.

Although it is possible to conduct the reaction at atmospheric pressure and even at super-atmospheric pressure, it is preferred, in the case of non-volatile acrylic acid products, to employ sub-atmospheric pressure when it is desired to separate the acrylate from the reaction mixture. Sub-atmospheric pressure also has the advantage of permitting lower reaction temperatures and faster rate of reaction. In a more preferred embodiment, the reaction is conducted under vacuum distillation conditions, in which event the non-volatile acrylic acid product is obtained in pure form as distillate. Volatile acrylic products, on the other hand, such as the free acid and ethyl ester, can be easily separated at atmospheric pressure so that reduced pressures are not as preferred in those instances. Also, when it is desired that the acrylate product be maintained in the reaction mixture, for example as a source of monomer for in situ polymerization, it will become advantageous to operate at atmospheric or super-atmospheric pressure during the pyrolysis reaction, wherein the cyanuric acid would sublime out of the reaction mass.

The pyrolysis reaction can be conducted either in the presence or absence of solvent. Suitable solvents will be high boiling materials which are inert under pyroly-

sis conditions and include N-methylpyrrolidone, tripropyl isocyanurate, Dowtherm and the like.

Reaction time will vary over a large range depending upon other reaction parameters and the extent to which 100 percent conversion is desired. Normally, the reaction must be conducted for at least 30 minutes to achieve an acceptable level of conversion, and it will be continued for up to several hours or several days until the desired extent of conversion is achieved. In this regard, it is noted that pyrolysis of the isocyanurates involves substantially more than mere melting of the reactant.

When conducting the instant pyrolysis under conditions conducive to separation of the acrylic acid product as it is formed, it will often be found that a quantity of cyanuric acid by-product sublimes over into the distillate receiver. However, the cyanuric acid is insoluble in the acrylic acid and it can be readily removed therefrom by filtration or other standard separation techniques.

Among the acrylic acid derivatives which are prepared by the instant process from the corresponding isocyanurate are the following:

- Acrylic acid
- Methyl acrylate
- Ethyl acrylate
- Propyl acrylate
- i-Propyl acrylate
- Amyl acrylate
- 2-Ethylhexyl acrylate
- n-Octyl acrylate
- n-Decyl acrylate
- Allyl acrylate
- Benzyl acrylate
- Cyclohexyl acrylate
- 2-Chloropropyl acrylate
- 2,3-Dichloropropyl acrylate
- Acrylamide
- N-Methyl acrylamide
- N-Ethyl acrylamide
- N-Isopropylacrylamide
- N-Benzylacrylamide
- N,N-Dimethyl acrylamide
- N,N-Diethylacrylamide
- Acryloyl chloride
- Acryloyl bromide
- Acrylic anhydride
- Acrylic acetic anhydride
- Acrylic propionic anhydride
- Acrylic benzoic anhydride
- Methacrylic acid
- Methyl methacrylate.

The reaction is especially advantageous for the preparation of acryloyl chloride, acryloyl bromide, chloroethyl acrylates and other acrylate derivatives difficult to prepare otherwise due to the unsaturation of the material.

The carboxyl-substituted isocyanurate reactants used in the instant invention are readily prepared by procedures taught by the prior art, or by obvious modifications to procedures taught by the prior art. For example, U.S. Pat. No. 3,235,553 disclosed the preparation of tris(2-carboxyethyl)isocyanurate and alkyl triesters thereof. Further methods for the preparation of the esters are disclosed in U.S. Pat. No. 3,322,945. Also, U.S. Pat. No. 3,432,500 discloses the

preparation of tris(2-carboxamidoethyl)isocyanurate and various substituted amides. By further reaction on these derivatives or modification of these procedures according to methods well known to those with ordinary skill in the art, other isocyanurate derivatives are readily available for pyrolysis to the desired acrylic acid compound. For example, the triallyl ester of tris(2-carboxyethyl)isocyanurate can be prepared and chlorinated and then pyrolyzed to afford either the monochloro or dichloropropyl acrylate. Additionally the tris(2-carboxyethyl)compound can be reacted with any of a variety of other carboxylic acids to afford an appropriate anhydride from which an acrylic acid anhydride can be prepared.

The following examples are provided to illustrate the instant invention more fully. They are provided for illustrative purposes only and are not to be construed as limiting the invention, which is defined in the appended claims. Variations and modifications in the procedures of the examples may be made by those with skill in the art without departing from the scope of the invention.

EXAMPLE 1

25 Tris(2-carboxyethyl)isocyanurate (17 g.) was placed in a vacuum distillation apparatus and heated at reduced pressure to 200° C. Heating was continued until 4 g. of acrylic acid was collected as distillate in a cold trap (71.5 percent yield on 53 percent conversion). Solid cyanuric acid, formed in the distillate by sublimation, was removed by filtration.

The pyrolysis reaction was also run with 0.1 g. of sodium hydroxide added to the reaction mixture with similar results.

EXAMPLE 2

40 Tris(2-carboxyethyl)isocyanurate (60 g.) was heated to 170°-200° C. in a distillation apparatus at atmospheric pressure until 23 g. of ethyl acrylate was collected as distillate (96 percent yield on 50 percent conversion). Continued heating of the distillation vessel afforded increased pyrolysis of the isocyanurate.

EXAMPLE 3

45 The octyl triester of tris(2-carboxyethyl)isocyanurate was prepared by heating octyl alcohol and the isocyanurate in the presence of 5 weight percent toluene until the theoretical amount of water had been removed. After removal of the toluene, the octyl triester (m.p. 24°-26° C.) was then pyrolyzed according to the procedure of Example 1 to afford octyl acrylate and cyanuric acid.

EXAMPLE 4

The procedure of Example 1 is repeated using the following isocyanurates to afford cyanuric acid and the corresponding derivative of acrylic acid:

- Tris(2-carboxypropyl)isocyanurate
- Tris(2-carboxamidoethyl)isocyanurate
- Tris(2-carboxyethyl)isocyanurate acid chloride
- Tris(2-carboxyethyl)isocyanurate acetic anhydride.

What is claimed is:

1. A process for the preparation of compounds of the formula:

wherein R_1 is hydrogen, methyl or ethyl and X is selected from the group consisting of halogen, $-OR_2$ wherein R_2 is hydrogen, alkyl, cycloalkyl, aryl or halogen-substituted alkyl, and $-NR_3R_4$ wherein R_3 and R_4 are independently selected from the group consisting of hydrogen, alkyl or aryl which comprises pyrolyzing an isocyanurate compound of the formula:

wherein R_1 and X have the meanings given above.

2. A process according to claim 1 wherein R_1 is hydrogen.

3. The process of claim 1 for the preparation of acrylic acid which comprises pyrolyzing tris(2-carboxyethyl)isocyanurate.

4. The process of claim 1 for the preparation of an alkyl acrylate which comprises pyrolyzing a tris(2-car-

balkoxyethyl)isocyanurate.

5. The process of claim 4 wherein said acrylate is ethyl acrylate and said isocyanurate is tris(2-carbethoxymethyl)isocyanurate.

5. The process of claim 1 for the preparation of an acrylamide which comprises pyrolyzing a tris(2-carboxamidoethyl)isocyanurate.

7. The process of claim 1 for the preparation of acryloyl chloride which comprises pyrolyzing the acid chloride of tris(2-carboxyethyl)isocyanurate.

8. The process of claim 1 wherein said pyrolysis comprises heating said isocyanurate at a temperature in excess of about 150° C. for a time in excess of about 30 minutes.

15. The process of claim 8 wherein the temperature of said pyrolysis is within the range of about 170°-250° C.

10. The process of claim 1 wherein said pyrolysis is conducted at sub-atmospheric pressure.

11. A process for the preparation of acrylic acid and 20 alkyl esters thereof which comprises heating tris(2-carboxyethyl)isocyanurate or a trialkyl ester thereof at a temperature within the range of about 170°-250° C. for a time in excess of 30 minutes.
